CLAIM

The ornamental design for a remote control with laser pointer and mouse, as shown and described.

DESCRIPTION

FIG. 1 is a front elevational view of a remote control with laser pointer and mouse showing my new design;

FIG. 2 is a rear elevational view thereof;

FIG. 3 is a top plan view thereof;

FIG. 4 is a bottom plan view thereof;

FIG. 5 is a left side view thereof;

FIG. 6 is a right side view thereof;

FIG. 7 is a perspective view thereof; and,

FIG. 8 is a perspective view thereof with the cap being a USB memory device detached for showing portion of the design not shown in other views.
